UNITED STATES PATENT OFFICE

166,722

DUPLEX HOUSE TRAILER

Richard Ten Eyck, Wichita, Kans.

Application February 16, 1951, Serial No. 14,237

Term of patent 14 years

(Cl. D14—3)

To all whom it may concern:

Be it known that I, Richard Ten Eyck, a citizen of the United States, residing in Wichita, Kansas, have invented a new and original Design for a Duplex House Trailer, of which the following is a specification, reference being had to the accompanying drawings, forming a part thereof, in which—

The characteristic features of my design reside in the interior portions, as shown by the broken away parts of Figures 1 through 4, inclusively.

I claim:

The ornamental design for a duplex house trailer substantially as shown and described.

RICHARD TEN EYCK.
